UNITED STATES PATENT OFFICE

ALBERT E. HUTT, OF NEW ROCHELLE, NEW YORK

COMBINATION DAY AND SLEEPING PASSENGER VEHICLE

Continuation of application Serial No. 252,748, filed February 8, 1928. This application filed September 24, 1928. Serial No. 308,063.

My invention is a continuation of my co-pending application Serial No. 252,748, filed February 8, 1928, and relates to a novel semi-double deck passenger carrying vehicle which is capable of accommodating a maximum number of seated passengers for a minimum of volumetric capacity and which does away with the present necessity of compelling passengers to stand in order to accommodate sufficient passengers for profitable operation, which is especially adapted at night to be converted into a sleeping coach.

My invention further relates to a novel construction which at night is adapted to be converted into a sleeping coach and which is equally applicable to all kinds of passenger carrying vehicles such as motor coaches, street cars and railroad carriages where a maximum seating capacity is desired.

20 My invention relates more particularly to a novel arrangement of seats located in two planes, the seats on the upper plane being positioned above those in the lower plane but facing in the opposite direction so as to reduce to a minimum the distance between said upper and lower seats thereby producing a "double deck" vehicle of a minimum overall height, which is readily adapted to be converted into a sleeping coach.

30 My invention further relates to a novel arrangement of upper and lower seats or sleeping berths without the need of upper and lower aisles or passageways and therefore without the need of a stairway, such as is used at present on double deck motor vehicles.

My invention further relates to a novel construction wherein a single aisle positioned intermediately of the upper and lower seats serves both said upper and lower seats and 40 which is so disposed that both the upper and lower seats can readily be reached from it, said seats being adapted to be converted at night into a sleeping coach.

My invention further relates to a novel vehicle adapted to be converted into a sleeping coach that can be built very near to the ground and still leave adequate clearance for the transmission of power from the power plant to the rear wheels due to the aisle being 50 located as stated in a higher plane than the

floor of the lower passenger carrying compartment.

My invention further relates to a novel vehicle structure of semi-double deck parlor coach type in which any pair of facing seats either upon the upper level or upon the lower level may be converted into a sleeping berth along lines similar to those now practiced upon railroad sleeping cars.

In the drawings:

Figure 1 represents a longitudinal sectional elevation taken upon the line 1—1 of Figure 6.

Figure 2 represents a sectional elevation taken on the line 2—2 of Figure 3.

Figure 3 represents a horizontal sectional plan view taken on the line 3—3 of Figure 2.

Figure 4 represents a cross sectional elevation taken on the line 4—4 of Figure 2.

Figure 5 represents a cross sectional elevation taken on the line 5—5 of Figure 2.

Figure 6 represents a cross sectional elevation taken on the line 6—6 of Figure 1.

Figure 7 represents an enlarged perspective sectional view showing one manner of supporting the upper and lower seats to enable them to be slid towards each other for use as a berth at night.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, wherein similar numerals of reference indicate corresponding parts, 1 represents my novel passenger carrying vehicle such as a motor coach of the semi-double deck parlor coach type having the roof 2, the sides 3 and 4, the bottom floor 5, and the longitudinal aisle or passageway 6, which is provided with suitably spaced steps 7 leading to the lower seats 10 arranged on either side of and

below said aisle or passageway 6 in pairs facing each other. A series of suitably spaced steps 8 lead from said aisle 6 to the upper seats 9, and are arranged on either side of said aisle and directly above and in vertical alignment with the lower seats 10. 11 and 12 designate front steps leading from the vehicle front platform 13 to the aisle 6. 16 represents lower stanchions for supporting the upper seats 9 and which serve as grab-handles for passengers entering and leaving the lower seats 10. The upper seats 9 are similarly provided with the upper stanchions 17 serving as grab handles for the passengers using said seats.

It will readily be seen from the above description that a passenger walking along the aisle 6 can with equal ease reach either an upper or a lower seat according to his preference or to whatever seats are available.

The above description more particularly relates to the use of the coach or vehicle by day, but at night it is desirable to convert any pair of opposing seats, as the upper seats 9 or lower seats 10, into a sleeping berth. Each seat is provided therebeneath with a longitudinal tongue 18 slideable in grooves or ways 19 which may be integrally formed or otherwise suitably secured with the sides or walls 3 and 4 of the vehicle, see Figure 7, whereby these members when required may be shifted from the position seen in Figure 1 to the position shown in Figure 2. The seat portions as 9 or 10 are slid towards each other and the lower seat backs 20 are then slid into the position seen in Figure 2. Mattresses 20* are then positioned upon the seat members for sleeping purposes. Curtains are employed for concealing these berths when made up, and as seen in Figures 2, 3, 4 and 5 a plurality of these vertically disposed curtains 21 are suspended from the car roof 2. These curtains 45 extend to the aisle 6 and one curtain conceals half of an upper and half of a lower berth, the meeting edges of two curtains being secured together by snaps 23 or the like. 24 designates removable transverse panels 50 whose contour and extent will be understood from Figures 2, 4 and 5. These panels extend from the roof 2 of the vehicle to the back of an upper seat to insure privacy in the upper compartments, when used as sleeping berths. The seats as 10 may be supported and guided in any suitable or conventional manner as will be understood from Figure 7 when they are slid towards each other as seen in Figure 2 to form berths, the construction seen in Figure 7 being omitted from the other views for the sake of clearness of illustration.

It will be noticed that I have shown the aisle 6 positioned nearer to the floor of the upper compartment and that I have placed

gaps 7 in this aisle to make steps to the lower compartments or seats. This necessitates passengers stepping over these gaps when walking along the aisle. These gaps, however, need only be twelve inches wide or even less and may be illuminated with safety lights so that obviously they will not be an accident hazard. It should be noticed, however, that I can just as well locate the aisle in another position relative to the upper and lower compartments and can either place gaps in it or make it continuous, whichever construction is best suited for the particular vehicle to be built, so that my invention is obviously not limited to the particular construction shown herewith.

While the vehicle typified in the drawings is a motor coach, the power plant, transmission, steering and other mechanisms have not been shown as they do not form part of the invention which is directed mainly to the passenger seating arrangement of the vehicle.

It will be further apparent that the seating and sleeping arrangement described herein can be applied with equal facility to electric street cars and also to steam and electric railroad carriages and the like, and in fact to a passenger carrying vehicle of any character.

It will be seen that when a passenger enters the vehicle by the conventional entrance door on the right side of the vehicle, that he mounts the front steps 11 and 12 which lead to the aisle 6 from which he can reach any of the upper seats 9 by mounting a step 8 or any of the lower seats 10 by descending a step 7. Should he wish to use the rear toilet 15 or wash room 15* he would use the step 14 at the rear end of the aisle 6. As the distance between the floors of the upper and lower compartment need only be approximately three feet, the aisle 6 could be located midway between them, in which case a passenger need only take either one step up or one step down to reach either an upper or lower seat or berth and there would be no need for any gaps in the aisle.

The compactness of a vehicle of this design will be readily apparent since the overall height need not exceed 8 feet, nine inches, which is the present height of many single deck busses. This low overall height and lowered center of gravity greatly adds to the stability of the vehicle and results in a much safer operation at higher speed by reason of a lower center of gravity than is now possible, all of which opens up a wider field for double deck vehicles than has existed up to the present time.

As will be understood from Figure 2 there is an appreciable space or distance between the backs of the upper berths, which is in vertical alignment with the central portion

of the lower berths, thereby affording standing room for the occupants of the latter.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent, is:—

- 15 1. The combination with a semidouble deck passenger carrying vehicle having a body, a single longitudinal aisle in said body, seats above and below said aisle, and steps leading from said aisle to said seats, of means for slidably securing said seats in position with respect to said body, whereby said seats may be slid into coacting position to form a sleeping berth, and removable panels adapted to form partitions intermediate adjacent berths.
- 20 2. The combination with a semidouble deck passenger carrying vehicle having a body, a longitudinal aisle in said body, vertically aligned seats above and below said aisle, and steps leading from said aisle to said upper and lower seats, of a sliding tongue carried by the bottom of each of said seats, guideways for engaging said sliding tongues, whereby said seats may be slid from their seat forming position into coacting position to form berths, and removable panels adapted to form a partition intermediate each pair of said upper seats, when said upper seats are in their berth forming position.
